UNITED STATES PATENT OFFICE

EDGAR H. SHELDON, OF MUSKEGON, MICHIGAN

FUME HOOD FOR LABORATORY TABLES

Application filed September 2, 1924. Serial No. 735,226.

My invention relates to fume hoods for laboratory tables.

One of the objects of the invention is to provide a simple, practical and efficient construction of fume hood.

Another object of the invention is to provide practical and effective means for withdrawing the fumes from the table.

Another object of the invention is to arrange for the effective control of the fumes.

In the accompanying drawings Fig. 1 is a side elevation of a portion of a laboratory table top and a fume hood thereon embodying my invention, parts of the hood being broken away for convenience of illustration;

Fig. 2 is a plan view of the same with parts broken away for convenience of illustration;

Fig. 3 is an end elevation of the same with parts broken away; and

Fig. 4 is a cross section taken on line 4—4 in Fig. 3.

Referring to the drawings, I show a portion of a table top 1 understood to be the top of a laboratory table or other device which is to be provided with a fume hood.

Mounted on the table 1 is the fume hood comprising end uprights 2 and 3, and a top or cover 4 mounted on and extending between the uprights 2 and 3. The top 4 comprises a supporting member or portion 5 conveniently constructed of end members 5a—5a and side members 5b—5b, connected with the end members 5a—5a. This top supporting member 5 is made hollow or tubular and is intended to receive the fumes rising from the table and the supporting standards or posts 2 and 3 are also hollow or tubular and are intended to receive the fumes from the

member 5 and conduct the same downwardly and away in any desired manner, as for example, through pipes 8—8 extending down from the under side of the table, the latter being provided with apertures 9—9 affording communication between standards 2 and 3 and pipes 8—8.

To permit fumes to enter the member 5 the sides 5b—5b thereof are provided with longitudinally extending slots 11—11 formed in the lower walls of the sides 5b—5b, and to

permit control of the fumes entering these slots and the concentration of the fumes as desired, dampers 12—12 are provided having controlling handles 14—14, whereby the slides 12—12 may be moved lengthwise of the members 5b to close different portions of these slots 11—11.

A table top plate 15 is provided, the same being secured at its edges to the member 5 and covering the space formed by said member 5. This prevents fumes from escaping through the area within the sides and ends of the member 5 and causes them to move outwardly and enter the slots 11—11, to which slots the fumes are drawn by suction applied to the pipes 8—8.

To take care of heavy fumes near the table top, dampers 17—17 are provided, said dampers having handles 18—18 by which they may be removed to provide openings on the inner sides of the uprights 2 and 3 at the points therein just above the table top 1.

From the foregoing it will be seen that a highly efficient fume hood construction is provided in which the movement of the fumes may be readily controlled by dampers. It will also be seen that the construction creates air suction currents at more nearly the points at which the fumes are created, and that less suction is required to accomplish fume elimination. Also that the shape of the ducts is such as to offer less resistance to the air currents as they pass down through the ducts.

It will be understood that changes and modifications may be made without departing from the spirit of the invention.

What I claim is:

1. A fume hood having a hollow member extending around its outer edge and provided with fume inlet openings, and uprights at the outer edges of said fume hood on which said hollow member is mounted, said uprights having fume ducts communicating with the interior of said hollow member.

2. A fume hood comprising hollow uprights and a top structure mounted thereon, said structure being provided with marginal fume inlets and also with ducts communicating with said inlets and also with said hol-

low uprights, and means controlling the entrance of fumes into said marginal inlets.

3. A fume hood comprising hollow uprights and a top structure mounted thereon, said structure being provided with marginal fume inlets and also with ducts communicating with said inlets and also with said hollow uprights, and means controlling the entrance of fumes into said marginal inlets, 10 said controlling means comprising sliding dampers.

4. A fume hood comprising hollow uprights and a top structure mounted thereon, said structure being provided with marginal fume inlets and also with ducts communicating with said inlets and also with said hollow uprights, and means controlling the entrance of fumes into said marginal inlets, 15 said uprights being provided with means at their lower ends for permitting heavy fumes to enter said uprights.

5. A fume hood comprising hollow uprights and a top structure mounted thereon, said structure being provided with marginal fume inlets and also with ducts communicating with said inlets and also with said hollow or tubular uprights, and means controlling the entrance of fumes into said marginal inlets, 20 said uprights being provided with means at their lower ends for permitting heavy fumes to enter said uprights, and means for controlling said last mentioned inlet means.

6. A fume hood comprising hollow uprights and a top member mounted thereon, 25 said top member consisting of an endless tubular member and a top plate extending across and secured to said tubular member so as to cover the space enclosed by the same, said tubular member being provided with longitudinally extending fume inlet openings and being mounted upon said hollow uprights at points between said longitudinally extending openings, the portions of said 30 tubular member mounted on said hollow uprights communicating with the interior thereof.

7. A fume hood comprising hollow uprights having flaring upper ends, a top member mounted on said uprights, said top member having a marginal duct whose sides are provided with fume inlets and whose ends communicate with said uprights so as to convey fumes from said inlets to said uprights, 35 and dampers controlling said fume inlets.

8. A fume hood comprising hollow uprights having flaring upper ends, a top member mounted on said uprights, said top member having a marginal duct whose sides are provided with fume inlets and whose ends communicate with said uprights so as to convey fumes from said inlets to said uprights, 40 and dampers controlling said fume inlets, said uprights being provided with

damper controlled inlets near their lower ends.

9. A device of the class specified comprising a substantially flat fume gathering structure composed of a substantially rectangular endless tubular member and a flat plate member supported by and secured to said tubular member and extending across the space enclosed by the same, said tubular member having its sides provided with longitudinally extending fume inlets and its ends provided with fume outlets and supporting members for said tubular member supporting the ends of said tubular member and provided with ducts communicating with the fume outlets in the ends of said tubular member.

10. A fume hood having a downwardly extending marginal rim having its bottom provided with fume inlets.

11. A fume hood provided with elevated fume inlets for the gases lighter than air and with relatively low inlets for gases heavier than air.

In witness whereof, I hereunto subscribe my name this 31st day of May, A. D., 1924.

EDGAR H. SHELDON.
